SHOE OUTSOLE

Meyer Margolin, Elgin, Ill.

Application September 3, 1943, Serial No. 501,047

3 Claims. (Cl. 36—33)

1

My invention relates to a novel shoe construction and more particularly my invention relates to a shoe outsole formed of wood or an equivalent substantially rigid material, constructed so that the necessary flexibility for the foot is provided.

Wood soles are employed in shoe manufacture, not only because of the unusual conditions resulting from the shortage of leather, but also because wood is a desirable material from the standpoint of novelty playshoes and their manufacture.

It is the object of the present invention to provide a shoe outsole of wood so constructed that proper foot play and flexibility is provided.

It is a further object of the present invention to provide a novel shoe outsole of wood that takes the place of the outsole, shank and heel base construction commonly employed.

It is a further object of the present invention to provide a shoe outsole that from a utilitarian standpoint is capable of substantially replacing leather.

It is a further object of the present invention to provide a flexible wooden outsole.

It is a further object of the present invention to provide a novel shoe outsole in which I provide proper transverse flexibility without allowing such play or looseness as would interfere with the proper use and wear of the shoe.

These objects, I accomplish by so jointing a wooden shoe outsole that the outsole bends at various points along its length, but the joints by which this bending is accomplished, are so interlocked that while there is a small amount of rotary movement, this rotary movement is restricted and limited.

I have also formed the entire shoe outsole, heel and arch structure of one piece of wood, thereby avoiding the multiplicity of operations and parts hitherto employed.

In the drawings,

Figure 1 is a side view of the shoe with the jointed outsole of my invention.

Figure 2 is a bottom view of the outsole of my invention.

Figure 3 is a side view of a shoe having a modified outsole of my invention.

Figure 4 is a bottom view of the outsole shown in Figure 3.

Figure 5 is a cross section taken along the line 5—5 of Figure 2.

Figure 6 is a diagrammatic cross section showing a modified form of my invention.

Figure 7 is a detailed side view of a modified

2

form of my invention in which adjacent sections of the outsole are hinged together.

Figure 8 is a side view of a modified form of my invention in which the rear part of the forepart of the shoe, the arch and heel are of wood and the forepart is of leather.

Figure 9 is a side view of a modified form of my invention in which a leather or rubber insert is provided in a wood outsole, taken along the line 9—9 of Figure 10.

Figure 10 is a plan view of the wooden outsole with the rubber or leather insert as shown in Figure 9.

Referring now more particularly to the drawings, in Figure 1 I show a shoe comprising an upper 10 and a wooden outsole 11. The wooden outsole comprises a section 12, comprising a heel and arch in one piece, and two jointed interlocking and interfitting sections 13 and 14.

Rubber lugs 15 extend through the outsole in contact with the insole to provide a resilience desirable for the non-compressive wood.

The joint between 13 and 14 is indicated at 17 and is in the form of a curve comprising interlocking fingers such as 18 and 19 which extend into recesses 20 and 21.

Because of this finger recess interlocking there can be no substantial free lateral movement or twisting of the shoe outsole, although a certain equivalent freedom of action is provided which is desirable from the standpoint of foot flexibility.

The joints at 17 and 22 provide sufficient flexibility for the forepart of the shoe so that it is substantially equal to the flexibility had in a leather shoe.

As seen in Figure 1, the portions of sections 13 and 14, at the joint 17, are beveled so that any dirt and gravel coming in contact therewith, would have no tendency to clog the opening, but would fall freely out of this beveled V-shaped opening.

In Figure 3, I show a shoe comprising an upper 25, and an outsole 26, comprising a heel portion and an arch portion and in jointed relation with 26 are outsole sections 27, 28, 29 and 30, which, as seen in Figure 4, are interlocked by means of square shaped finger projections and corresponding recesses.

As seen in Figure 4, 32 is a typical projection which extends into a recess 33. This allows but a very limited side movement and keeps the flexible joints in the outsole made up of such joints in a straight line, thus avoiding wear and tear on the element or elements that secure the jointed parts together, which may for example

comprise a fabric or leather cover element secured at the top of the joints in the position of an insole, or this joint element may comprise a rubber insert set into the wooden outsole and attached to the various jointed parts thereof.

Rubber lugs 34 disposed at various locations throughout the outsole provide a flexibility and softness that is transmitted from the ground to the insole.

Figure 5 shows a detailed cross section in which an insole 40 is set into an outsole generally denoted as 41, insole 40 being secured to the separate segments of sections 41, 42, 43, 44 and 45. The insert 40 may be of leather, fabric or rubber and is firmly secured by adhesive or the like securing means to the various wooden sections that comprise the outsole. When the insert is of rubber, it provides a softness and resilience for the foot that plays a great part in making the wooden outsole satisfactory for the purposes described.

To enhance that softness and cushioning effect, I provide a multiplicity of rubber lugs 47 which help to form a path through the non-compressive wood between the insert 40 and the ground.

For this purpose the lugs 47 extend slightly below the level of the outsole.

In Figure 6, I show a similar construction but in which the lugs 48 are set into the outsole and do not extend up into contact with the insole. The proper distribution of these rubber or resilient lugs at suitable intervals throughout the outsole give the wooden outsole a desirable softness and yieldability. The rubber lugs 48 do not contact the insert 49 which holds the various wooden sections 50 but they do improve the property with regard to the softness.

In Figure 7, I show a detailed view of a structure in which the interlocking finger and recessed joints such as 52 and 53 are interlocked with a rod element 54, this rod extending through the extending fingers and through the recesses of the interlocking joints so that the proper swivel action of the joints is obtained.

In Figure 8 I show a shoe comprising an upper 60 and an outsole comprising an outsole portion 61 formed of wood which comprises the heel portion 62 and the arch portion 63 and a part of the forepart 64. Secured to the portion 61 in any suitable manner is a leather forepart portion 65. In lieu of leather some other flexible and/or resilient material, such as a plastic mix, may be employed. Thus, by the use of the relatively small amount of leather embodied in portion 65, I get most of the desirable properties of flexibility and resilience of the leather outsole.

In Figure 9 I show a wooden outsole 70 with an insert 71 disposed in a recess 72 in said outsole 70. The insert 71 may comprise leather or rubber or some other resilient material which provides the proper foot comfort. It is desirable when an all-over wood outsole is employed, jointed in whatever way is necessary to give flexibility, that foot comfort be provided in the form of a soft and resilient forepart ball portion.

By the structures shown herein, I provide a shoe having a wooden outsole with many unusual properties, more particularly flexibility for the

foot in the proper manner as the foot breaks in walking; softness, resilience, and foot comfort; control of the jointed outsole and shoe to prevent twisting, tearing and disengagement.

Various other modifications of my invention will suggest themselves to those skilled in the art. I accordingly desire that in construing the breadth of the appended claims they shall not be limited to the specific details shown and described 10 in connection with the above explanation.

I claim:

1. An outsole comprising joints of a substantially rigid material, the upper surface of said outsole being recessed, a resilient insert disposed in said recess, said resilient insert comprising means for securing said joints to one another, openings in said outsole extending vertically and completely through said outsole, and resilient plugs disposed into said openings said resilient plugs being of sufficient length and positioned so as to be in direct contact with the resilient insert at their upper end and to extend to the outer surface of the outsole at their lower or opposite end.

2. An outsole comprising joints of a substantially rigid material, the upper surface of said outsole being recessed, a resilient insert disposed in said recess, said resilient insert comprising means for securing said joints to one another, openings in said outsole extending vertically and completely through said outsole, and resilient plugs disposed into said openings, said plugs contacting said resilient insert at their upper end and extending slightly beyond the lower surface of the outsole at their lower or opposite end.

3. An outsole comprising joints of a substantially rigid material, the upper surface of said outsole being recessed, a resilient insert disposed in said recess, said resilient insert comprising means for securing said joints to one another, openings in said outsole extending vertically and completely through said outsole, and resilient plugs disposed into said openings, said plugs contacting said securing means at their upper end and extending slightly beyond the lower surface of the outsole at their lower or opposite end.

MAYER MARGOLIN.
